(57) **CLAIM**

The ornamental design for a control unit for a peristaltic pump, as shown and described.

DESCRIPTION

FIG. 1 is a perspective view of an embodiment of the control unit for a peristaltic pump showing my new ornamental design;

FIG. 2 is a front view of an embodiment of the control unit for a peristaltic pump showing my new ornamental design;

FIG. 3 is a rear view of an embodiment of the control unit for a peristaltic pump showing my new ornamental design;

FIG. 4 is a left side view of an embodiment of the control unit for a peristaltic pump showing my new ornamental design;

FIG. 5 is a right side view of an embodiment of the control unit for a peristaltic pump showing my new ornamental design;

FIG. 6 is a top view of an embodiment of the control unit for a peristaltic pump showing my new ornamental design; and,

FIG. 7 is a bottom view of an embodiment of the control unit for a peristaltic pump showing my new ornamental design. Portions of the claimed design shown in broken lines form no part of the claimed design.
